Primary Examiner — Cathron C Brooks(74) *Attorney, Agent, or Firm* — Leydig, Voit & Mayer, Ltd.(57) **CLAIM**

The ornamental design for a display screen with graphical user interface, as shown and described.

DESCRIPTION

The FIGURE is a front view of a display screen with graphical user interface showing our new design.

The outermost broken line rectangle illustrates a display screen. The remaining broken lines illustrate portions of the graphical user interface. None of the broken lines form part of the claimed design.
